(57) **CLAIM**

The ornamental design for a pool cleaner, as shown and described.

DESCRIPTION

FIG. 1 shows a rear view of a pool cleaner according to the present invention.

FIG. 2 shows a front view of the pool cleaner of FIG. 1.

FIG. 3 shows a perspective view of the pool cleaner of FIG. 1.

FIG. 4 shows a bottom view of the pool cleaner of FIG. 1.

FIG. 5 shows a right side view of the pool cleaner of FIG. 1.

FIG. 6 shows a left side view of the pool cleaner of FIG. 1.

FIG. 7 shows another perspective view of the pool cleaner of FIG. 1; and,

FIG. 8 shows a top view of the pool cleaner of FIG. 1.

Portions or features of the pool cleaner not shown in the drawings form no part of the claimed design. Portions or features of the pool cleaner shown in broken lines form no part of the claimed design.
